(57) **CLAIM**

The ornamental design for a single piece foam band for a face shield, as shown and described.

DESCRIPTION

FIG. 1 shows a perspective view of face shield according to an exemplary embodiment;

FIG. 2 shows a top view of face shield according to an exemplary embodiment;

FIG. 3 shows a rear view of face shield according to an exemplary embodiment;

FIG. 4 shows a side view of face shield according to an exemplary embodiment;

FIG. 5 shows a perspective view of face shield according to an exemplary embodiment;

FIG. 6 shows a top view of face shield according to an exemplary embodiment;

FIG. 7 shows a rear view of face shield according to an exemplary embodiment; and,

FIG. 8 shows a side view of face shield according to an exemplary embodiment.

Any broken line illustration is not part of the design sought to be patented.
